UNITED STATES PATENT OFFICE.

GEORGE F. SISBOWER, OF FLUSHING, AND LOUIS E. PITTONI, OF NEW YORK, N. Y.,
ASSIGNORS TO MANHATTAN-ROME COMPANY, BRANCH OF ROME METALLIC BED-
STEAD CO., OF LONG ISLAND CITY, NEW YORK, A CORPORATION OF NEW YORK.

CONVERTIBLE BED.

1,419,319.

Specification of Letters Patent. Patented June 13, 1922.

Application filed March 11, 1921. Serial No. 451,510.

To all whom it may concern:

Be it known that we, GEORGE F. SISBOWER, a citizen of the United States, residing at Flushing, in the county of Queens and State of New York, and LOUIS E. PITTONI, a subject of the King of Italy, residing at New York city, in the county of Queens and State of New York, have invented certain new and useful Improvements in 10 Convertible Beds, the following being a full, clear, and exact disclosure of the one form of our invention which we at present deem preferable.

For a detailed description of the present 15 form of our invention, reference may be had to the following specification and to the accompanying drawings forming a part thereof, wherein—

Fig. 1 is a side elevation of the frame-work of our device;

Fig. 2 is a plan of one end of the mattress wire fabric;

Fig. 3 shows the open or distended position of the frame, and

Fig. 4 shows it in an intermediate position.

Our invention resides in a folding or convertible bed that may be made into a chair for day use—a davenport being considered 30 as a wide chair. To this end we provide three frames, one of which forms the back of the chair and also an approximate third of the bed; while the other two frames are nested one within the other to form the 35 seat of the chair but are opened out away from each other to form the other two-thirds of the bed. In particular, we have devised a special form of link-and-lever connection for these frames which we have 40 found to be superior in most respects to any now known to us, especially as regards ease and certainty of operation, also simplicity, strength and cheapness of construction.

Referring to the drawings, A represents 45 the middle or seat-frame; B the extension frame wherein the seat-frame is nested when the chair is formed, and C the frame which forms the back of the chair or one end of the bed. D represents a deep U-bar 50 which at each end of the bed is pivoted at its outer ends to the inner edge of frame B and at its inner part which is widened or branched by brackets d^1 d^2 , it is movably connected at two points to two other points

on the horizontal cross-bar A^2 of frame A 55 by means of two crossing links X and Y. The widening brackets d^1 and d^2 are riveted to the inside of each leg of the U-bar D, as is shown in Fig. 2. To one end of each link X and Y is connected a spring, the two 60 springs being denoted by 1 and 2, and these springs are connected at their opposite ends to the aforesaid cross-bar A^2 . The spring 1 resists the movement of link X around its point of connection with the cross-bar 65 when the frame B is coming to its extended position, shown in Fig. 1, while spring 2 acts similarly on link Y when frame B is coming to its closed or nesting position, shown in Fig. 1. By this arrangement the 70 springs aid the start and resist the finish of both movements. It requires but a slight push to start either the opening or closing while the finish of both movements is cushioned so as to bring the parts gently to 75 rest. The U-bar D not only serves as the connecting agency between the frames A and B but also serves as a side bar for frame B to resist the longitudinal pull of the wire mattress fabric. 80

The back frame C is jointed directly to one corner of the frame A and is curved downward at its inner end. To this inner end is pivoted one end of link F, the other end of this link being pivoted to the aforesaid bar D at a point somewhat more than half way down from its outer end. The frame C is also provided with pivoted legs each of which is operated by a link G which acts to draw the leg in close to the back, 90 as shown in Fig. 1 when the frames are closed together to form a chair. Each of the three frames A, B and C is provided individually with a wire mattress fabric as shown in Fig. 2. 95

What we claim as new and desire to secure by Letters Patent is:

1. A convertible bed comprising two frames which may be nested to form a seat, an intermediate member at each end of the 100 seat pivoted at one side to a point on one frame and at its other side widened and connected to the other frame at two points by means of links, springs for aiding the start and retarding the finish of both opening and closing movements and a third frame forming a back for said seat, the third frame pivoted to one of said nesting 105

frames and linked to the said intermediate member.

2. A convertible bed comprising two frames which may be nested to form a seat, 5 an intermediate member at each end pivoted to one point on one of said frames and connected by links to two points on the other frame, springs for aiding the start and resisting the finish of both opening and closing 10 movements together with a third frame pivoted to one of said nesting frames to form a back for the seat and linked to said intermediate member.

3. A convertible bed comprising two 15 frames which may be nested to form a seat, an intermediate member in the form of a U-bar the ends of which are jointed to one of the said frames, links at each end of the seat connecting two points on said member 20 to the other frame, a third frame forming a back for the seat and linked to said member

and springs acting to aid the start and retard the finish of both opening and closing movements.

4. A convertible bed comprising two 25 frames which may be nested to form a seat, an intermediate member in the form of a U-bar constituting a strut for one side of one of said frames and jointed thereto at its ends, brackets on said member, links joining said brackets respectively to the other frame, a third frame forming a back for the seat and linked to said member and springs acting on said links to aid the start and resist the finish of both opening and 30 closing movements.

Signed at Long Island City, county of Queens, State of New York, this 10th day of March, 1921.

GEORGE F. SISBOWER.
LOUIS E. PITTONI.
